SPENCER PHILIP HARRY, OF LONDON, ENGLAND, ASSIGNOR TO THE MONARCH TYPE WRITER COMPANY, OF SYRACUSE, NEW YORK, A CORPORATION OF NEW YORK.

TYPE-WRITING MACHINE.

1,021,835.

Specification of Letters Patent.

Patented Apr. 2, 1912.

Application filed December 28, 1911. Serial No. 668,242.

To all whom it may concern:

Be it known that I, SPENCER P. HARRY, a subject of the King of Great Britain and Ireland, and resident of London, England, 5 have invented certain new and useful Improvements in Type-Writing Machines, of which the following is a specification.

My invention relates to ribbon spools for writing machines and has for its object to 10 provide a new and improved ribbon spool, and one which is particularly adapted for the ready attachment and detachment of the ribbon in roll form.

In many styles of typewriting machines 15 the spools on the machine on which the ribbon is wound have mounted upon them devices which operate automatically when the ribbon is completely unwound, to effect the reverse of the ribbon or change in the direction of its longitudinal feed. These spool-carried reversing devices make the spools comparatively expensive, and consequently 20 it is not commonly practicable to supply new spools of regular pattern with each ribbon 25 but, instead, the ribbons are furnished on cheap supply spools and are wound therefrom on to the regular working spools, an operation which is both tedious and time-consuming and also soils the hands of the 30 operator.

One of the chief objects of my present invention is to obviate these defects and in carrying out this object I provide a regular machine spool with a head or flange which 35 is readily detachable from the hub portion of the spool, and associate with this hub portion a core device on which the ribbon is wound and which device may be readily removed and replaced, the construction and 40 arrangement being such that when the core device with the ribbon wound thereon is applied to the hub the reversing device which extends axially of the spool close to the hub is received between the core and the inner 45 fold, ply or end portion of the ribbon wound upon said core device. Consequently when the ribbon has been unwound the reversing device will be free to operate automatically in the usual manner to reverse the direction 50 of feed of the ribbon.

My invention will be explained in detail in connection with the accompanying drawing which illustrates one form of my invention, and in which—

55 Figure 1 is a sectional view of a ribbon

spool to which my invention is applied, the section being taken parallel to the spool flanges on a plane represented by the dotted line *y* in Fig. 2 and looking in the direction of the arrows at said line. Fig. 2 is a sectional view taken on a plane represented by the dotted line *x*—*x* in Fig. 1 and looking in the direction of the arrows at said line. Fig. 3 is a sectional view corresponding to Fig. 2 but showing the ribbon completely unwound 65 and the reversing devices which are attached to the spool in operative position. Fig. 4 is a plan view of the detachable spool head or flange. Fig. 5 is a perspective view of the container or core device on which the ribbon 70 is wound and which device is attachable to and detachable from the spool proper.

While my invention may be applied to various styles of writing machine spools, I have preferred to show it herein as applied 75 to a spool of a pattern adapted for use in the Monarch typewriting machine and provided with ribbon reversing devices of the character employed in said machine and disclosed in the patent to George B. Brand, 80 No. 960,804, granted June 7, 1910.

In the drawing, 1 indicates a circular disk-like spool head or flange which in the present instance is the under or lower flange that is seated at the bottom of the usual 85 spool cup of the Monarch machine. Pivoted to the under face of the flange 1 is a reversing cam plate 2 which normally is held in contact with the under face of the flange by a horizontally disposed arm 3 of 90 a reversing device or bell crank lever which is fulcrumed at 4 to the flange 1 and further includes an upright arm or portion 5 which extends through a slot in the flange 1 and is adapted to coöperate with the inner end 95 portion or fold of the ribbon.

The hub portion of the present spool comprises a plurality of posts or pins 6 permanently fixed to and projecting upward from the head or flange 1. A set of three posts is 100 shown in the present instance, the set being 105 triangularly arranged and each post terminating in a head 7 which is rounded and somewhat pointed at the top and is joined to the body of the post by a comparatively 105 thin neck portion 8. The spool further comprises a detachable flange or head 9 provided with holes or openings 10 designed for coöperation with the posts. The holes 10 are 110 triangularly arranged in correspondence

with the posts 6 but the distance between them is slightly less than the distance between the posts when the flange 9 is detached. Consequently when the flange 9 is applied to the posts and the pointed heads, thereof engage with the holes 10 it will be necessary to press the flange 9 downward or toward the flange 1 with a sufficient pressure to force the heads 7 toward each other far enough to permit them to pass through the holes 10, the posts 6, while substantially rigid, having sufficient spring or "give" for the purpose. When the heads have passed through the holes the inherent spring in the posts will cause them to spring apart until the neck portions 8 engage with the walls of the holes 10 at the points farthest from the axis of the spool as will be clearly understood from Figs. 2 and 3. The shoulders 11 formed by the junction of the bodies of the posts 6 with the associate necks 8 will limit the movement of the flange 9 toward the flange 1. With the holes 10 in coöperation with the necks 8 the flange 9 will be confined between the shoulders 11 and the under side of the heads 7, and will be frictionally engaged with the necks 8. Thus the flange 9 is frictionally connected to the hub portion of the spool, the construction being such that while the flange 9 may be readily detached and attached, it is nevertheless when in place on the spool, securely connected thereto and maintained at a proper and predetermined distance from the flange 1 by the hub comprising the set of headed posts.

The spool proper may be said to comprise the two flanges 1 and 9 and the connecting hub portion or posts 6; but the spool contrivance or spool as a whole further comprises a detachable or disconnectible ribbon carrier, container or core device which is designed to fit loosely over the hub portion or posts 6. The core device, which is clearly shown in Fig. 5 where it is designated as a whole by the numeral 12, is preferably made of a single piece of sheet metal bent or folded to a general triangular shape and having its ends suitably connected as by a rivet 13. One of the sides 14 of the core device is depressed or bent inward toward the center and the ends of this side terminate in outward projections or lugs 15, each comprising two thicknesses or plies of the metal. One of the other sides is punched to provide a set of prongs 16 or attaching devices for the inner end of the ribbon 17. The end of the ribbon having been attached to the core 12 by being hooked over the prongs 16, its first fold or ply will, as clearly shown in Fig. 1, pass over and around the projections 15, thus providing a considerable space or opening designated as 18 in Fig. 1 between the inner face of the first ribbon ply and the face of the side or wall 14 of the core device.

It will be understood that the ribbon is wound around the core device in a continuous series of folds or plies. Thus the core device becomes a container or carrier proper for the ribbon and facilitates the bodily introduction of the ribbon to the spool and the removal of the ribbon as a whole therefrom. The triangular core device is of such dimensions that it fits readily over the triangularly disposed set of posts 6 but cannot turn thereon or relatively thereto to any appreciable extent.

Supposing it be desired to apply a ribbon to the spool, the flange 9 is removed and a core device 12 having a ribbon fully wound thereon is slipped down or entered over the posts 6. During this operation the upright arm 5 of the releasing device or lever is pressed in by the operator so as to maintain the cam plate 2 against the flange 1 as in Fig. 2 and the core device is thereupon arranged so that the arm 5 will extend upward through the space 18 between the ribbon and the side 14, as will be clearly understood from Figs. 1 and 2. From these figures it will be apparent that when the operator releases the arm 5 after having slipped the core device in place, said arm will still be maintained in the position shown in Figs. 1 and 2 by reason of its contact with the inner end portion, fold or ply of the ribbon 17, which fold acts as a stop for the arm. Thereafter the flange 9 may be replaced, the headed ends of the posts serving as latching devices to detachably connect said flange to the spool and the core device and ribbon being then confined to the spool between the flanges 1 and 9. The upright shaft on which the ribbon spool is detachably mounted through holes 19 in the spool flanges and from which the spool receives turning or rotary movements during the operation of the machine is not shown herein but is or may be of the usual Monarch construction or of any other suitable construction. It will be understood that when in the course of printing operations the ribbon is completely unwound from the core or carrier 12 it will free the upright arm or releasing device 5 and permit the cam plate 2 to drop down to operative position for coöperation with the other releasing devices of the Monarch machine as set forth in the aforesaid patent to Brand.

It will be seen that I provide a novel ribbon spool which comprises a detachable flange connectible to and disconnectible from the spool with readiness and facility, the construction being such that it enables a core device, ribbon carrier or container to be quickly and conveniently applied to and removed from the spool proper; that the ribbon is wound on the detachable core so as to provide a space between the core and the ribbon for the reception of a reversing de-

vice which is mounted on the spool proper; or, in other words, that the core device is so constructed and the ribbon is so arranged on it that when the core device supplied with a ribbon fully wound thereon is applied to the spool the ribbon will confine in inoperative position the reversing device which the spool carries, but will, when fully unwound, release said reversing device so that it may effect a reversal of the ribbon.

Thus my invention provides a ribbon spool construction which greatly facilitates ribbon renewals, and also a construction which is especially suitable for a ribbon spool supplied with reversing mechanism, enabling a ribbon to be put in place and removed with facility and despatch without interfering with the proper operation of the ribbon reversing mechanism.

Various changes may be made without departing from the spirit and scope of my invention.

What I claim as new and desire to secure by Letters Patent, is:—

1. A ribbon spool for writing machines comprising a flange, a hub, said flange and said hub being rigidly related, and a second flange detachable from said rigid hub, said rigid hub alone maintaining the two flanges properly spaced apart.

2. A ribbon spool for writing machines comprising two flanges and a hub, and latching devices integral with said hub for detachably connecting one of said flanges, said latching devices serving to maintain a detachable flange in proper working relationship to the other flange.

3. A ribbon spool for writing machines comprising two flanges and a connecting hub, one of said flanges being frictionally connected to said hub and the other flange being rigidly connected to said hub, said frictionally connected flange being maintained at a predetermined distance from the other flange by the rigid hub alone.

4. A ribbon spool for writing machines comprising a head or flange, a post or pin permanently and rigidly fixed to said head, and a second flange frictionally connected to said post and in part maintained by a device integral with said post at a predetermined distance from the first named flange, said device preventing movement toward or away from the first named flange.

5. A ribbon spool for writing machines comprising a head or flange, a plurality of posts permanently secured to said head, and a detachable head engaging said posts.

6. A ribbon spool for writing machines comprising a head or flange, a plurality of posts secured thereto, and a detachable head provided with holes frictionally engaging the outer ends of said posts.

7. A ribbon spool for writing machines comprising a head or flange, a plurality of

posts secured thereto and provided with grooved outer ends, and a detachable head formed with holes in which the grooved ends of said posts engage under tension.

8. A ribbon spool for writing machines comprising a head or flange, a plurality of posts secured thereto and provided with grooved outer ends, and a detachable spool flange formed with holes in which the grooved ends of said posts engage, the holes being so spaced as to draw the posts toward each other and cause frictional engagement between them and the detachable head.

9. A ribbon spool for writing machines comprising a head or flange, three posts or pins secured thereto, said posts being triangularly arranged and terminating in rounded heads or ends connected by necks of lesser diameter with the body portions of the posts, and a detachable spool flange provided with holes for engaging the heads of the posts.

10. A ribbon spool for writing machines comprising a flange, three posts or pins secured thereto, said posts being triangularly arranged and terminating in rounded heads or ends connected by necks of lesser diameter with the body portions of the posts, and a detachable spool flange provided with holes for engaging the heads of the posts, the holes being spaced apart distances slightly less than the distance between the post heads so that when the detachable flange is forced into engagement with the necks of the posts it will be maintained frictionally connected thereto.

11. A ribbon spool for writing machines comprising a flange, three triangularly arranged posts secured to said flange and each terminating in a rounded head, a detachable spool-flange provided with holes engaging the heads of the posts, and a detachable core device adapted to fit over said heads.

12. A ribbon spool for writing machines provided with a hub and carrying a ribbon reversing device extending along the hub, and a detachable core device on which the ribbon is wound, said core device being adapted to be arranged upon the hub with said ribbon reversing device in direct engagement with the inner end portion of the ribbon.

13. A ribbon spool for writing machines provided with a hub and carrying a ribbon reversing device adjacent to the hub, a detachable core device on which the ribbon is wound, said core device being adapted to be arranged upon the hub with said ribbon reversing device in direct engagement with the inner end portion of the ribbon, and a detachable spool-flange co-operating with the hub to hold the ribbon in place on the spool.

14. A ribbon spool for writing machines provided with a ribbon reversing device, and a disconnectible core device on which the

ribbon is wound, attachable so that the inner folds of the ribbon may coöperate with the ribbon reversing device to retain it in inoperative position.

5 15. A ribbon spool for writing machines comprising parallel flanges and a connecting hub portion, devices for affording a ready attachment and detachment of one of said flanges, and a detachable core device associated with said hub portion and on which the ribbon is wound.

15 16. A ribbon spool for writing machines comprising a removable flange or head, latching devices for detachably connecting said flange to the spool, and a core device on which the ribbon is wound, said core device being loose on the spool and readily detachable after said flange has been removed.

20 17. A ribbon spool for writing machines comprising parallel flanges one of which is removable and frictionally connected to the spool, and a core device on which the ribbon is wound, said core device being readily detachable after the removable flange has been

25 18. A ribbon spool for writing machines comprising a head or flange, a plurality of posts permanently secured to said head, a second head detachably engaging said posts, and a removable core on which the ribbon is wound, said core being confined between said heads.

30 19. A ribbon spool for writing machines provided with a ribbon reversing device, and

a core device on which the ribbon is wound, 35 attachable so that the ribbon will confine the reversing device to inoperative position but will when fully unwound release said device so that it may effect a reversal of the ribbon.

20 20. A ribbon spool for writing machines 40 comprising a detachable core on which the ribbon is wound so as to provide a space between the core and the ribbon for the reception of a reversing device.

21 21. A ribbon spool for writing machines 45 comprising a detachable core on which the ribbon is wound so as to provide a space between the core and the ribbon for the reception of a reversing device mounted on the spool proper and extending along the 50 core.

22 22. A ribbon spool for writing machines comprising a flange carrying a reversing cam, a reversing lever fulcrumed on said flange and coöperating with same cam, a 55 second flange detachably connected to the first flange, and a movable core device on which the ribbon is wound, said core device being received between the flanges, while the reversing lever enters a space between 60 said core device and the ribbon.

Signed at London, England, this sixth day of December A. D. 1911.

SPENCER PHILIP HARRY.
